UNITED STATES PATENT OFFICE.

GERTRUDE M. BERENTSEN, OF WAUWATOSA, WISCONSIN.

SEAT COVER FOR INFANTS' TOILETS.

Application filed July 15, 1927. Serial No. 206,073.

This invention relates to improvements in seat covers for infants' toilets.

It is one of the objects of the present invention to provide a seat cover for infants' toilets which renders the seat sanitary, and which protects the infant and its clothing.

A further object of this invention is to provide a seat cover which will serve as a support to hold the infant in place.

10 A further object of this invention is to provide a seat cover which will add to the comfort of the child.

15 A further object of this invention is to provide a seat cover which is of very simple construction, is inexpensive to manufacture, and is well adapted to the purpose described.

20 With the above and other objects in view, the invention consists of the improved seat cover, and its parts and combinations as set forth in the claim and all equivalents thereof.

25 In the accompanying drawing in which the same reference characters indicate the same parts in all of the views:

20 Fig. 1 is a side view of the seat cover as attached to the seat showing the parts in position for use with the attaching and supporting flap secured to a garment;

30 Fig. 2 is a plan view of the seat cover detached, part being broken away; and

Fig. 3 is a front view of the seat cover with the flaps in position, the upper one being attached to a portion of the infant's garment.

35 Referring now more particularly to the drawing, it will be seen that the seat cover comprises a main seat portion 4, having a central opening 5, and complementary fastening members 6 around its periphery, and having a front upper flap 7 formed with safety pin openings 8. A front lower flap 9, having a U-shaped inner end portion 10 to fit

around the central opening of the main seat portion is fastened to the under surface of the main portion at 11. The seat cover is 45 constructed preferably of a rubberized or waterproof material.

In use, the cover is attached to the seat by means of the complementary fastener openings 6. As the seat cover is of a flexible 50 material, it will sag downwardly through the opening of the seat, and thus give a cushioning effect which will add greatly to the comfort of the baby. The lower flap 9 is allowed to hang downwardly into the receptacle, and the flap 7 is pinned to a portion of the infant's garment as is shown in Figs 55 1 and 3. The main portion 4 serves as a sanitary protection for the seat, the flap 7 serves as a support for the baby and also as 60 a sanitary protection for its garments, and the flap 9 serves as a guide into the receptacle.

From the foregoing description it will be seen that the improved seat cover is of very 65 simple and novel construction, and is well adapted for the purpose set forth.

What I claim as my invention is:

A seat cover for toilets of a flexible, 70 waterproof material, which yieldingly sags within the opening of the toilet seat to cushion the user, comprising a main seat portion having a central opening considerably smaller than the opening of the toilet seat, and having a front upper flap, means on the 75 main seat portion for securing it to the toilet seat, means on the upper flap for securing it to a garment of a user, and a front lower flap attached at its inner end to the main seat portion and adapted to extend 80 vertically toward the toilet receptacle.

In testimony whereof, I affix my signature.

GERTRUDE M. BERENTSEN.
